(57) **CLAIM**

The ornamental design for a bracket lamp, as shown and described.

DESCRIPTION

FIG. 1 is a perspective view including a front, right and top side of a bracket lamp showing my new design;

FIG. 2 is a perspective view including a rear, left and bottom side of the bracket lamp;

FIG. 3 is a left side elevation view of the bracket lamp;

FIG. 4 is a right side elevation view of the bracket lamp;

FIG. 5 is a front elevation view of the bracket lamp;

FIG. 6 is a rear elevation view of the bracket lamp;

FIG. 7 is a top plan view of the bracket lamp;

FIG. 8 is a bottom plan view of the bracket lamp; and,

FIG. 9 is an enlarged detail view of the encircled portion of FIG. 2.

The dot-dash broken lines in FIGS. 2 and 9 delineate a portion of the claimed design that is shown on an enlarged scale in FIG. 9. The portions of the Figures shown in phantom lines are for illustrative purpose only and form no part of the claimed design.
